CLAIM

The ornamental design for a coupling for process cartridge
for image forming apparatus, as shown and described.

DESCRIPTION

FIG. 1 is a front elevation view of a coupling for process
cartridge for image forming apparatus showing our new
design;

FIG. 2 is a rear elevation view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a bottom, front, and left side perspective view
thereof; and,

FIG. 8 is a top, rear, and right side perspective view thereof.

1 Claim, 8 Drawing Sheets
